UNITED STATES PATENT OFFICE.

LELAND A. DUBBS, OF INDEPENDENCE, KANSAS, ASSIGNOR TO UNIVERSAL OIL PRODUCTS COMPANY, OF CHICAGO, ILLINOIS, A CORPORATION OF SOUTH DAKOTA.

PROCESS FOR TREATING HYDROCARBON OILS.

1,319,053.

Specification of Letters Patent.

Patented Oct. 21, 1919.

Application filed January 14, 1918. Serial No. 211,710.

To all whom it may concern:

Be it known that I, LELAND A. DUBBS, a citizen of the United States, now residing in the city of Independence, county of Montgomery, and State of Kansas, have invented certain new and useful Improvements in Processes for Treating Hydrocarbon Oils, of which the following is a specification.

This invention relates to a method for 10 treating hydrocarbon oils to produce therefrom products having lower boiling points.

Among the salient objects of the invention are: to provide a process wherein the oil under treatment is circulated through 15 a coil, or series of coils, in which the oil is heated and then distilled, and through said same coils is circulated a non-re-active abrasive material by mixing same with the oil and acting to prevent the deposits of carbon or other solid matter collecting and adhering to the inner walls of these coils, and also acting to polish the inner surface of these coils during the time the oil, while 20 circulating in these coils, is subjected to such pressure and temperature necessary 25 for producing lower boiling point products therefrom; to provide a method wherein this abrasive material mixed with the oil can be settled out and separated from the 30 oil while said oil is undergoing treatment for the production therefrom of lower boiling point products; to provide a method whereby an abrasive material can be mixed with the oil while said oil is undergoing 35 treatment, said abrasive material being injected into the oil at some point between the discharge of the circulating pump and the first heating coils and withdrawing the abrasive material from the oil before said 40 oil again enters the suction side of the circulating pump; to provide in general a process of the character referred to.

In the drawings:

Figure 1 is a side elevation of the apparatus partly in section and partly broken away.

Fig. 2 is a plan view showing one end of the heating and distilling coils, the carbon settling tanks, the circulating pump and 50 connections, and top view of hopper where the abrasive material is mixed with the oil.

Fig. 3 is one end view of the heating and distilling tubes.

Referring to the drawings; A¹ is the fur-

nace in which the distilling tubes are positioned; A² is the furnace in which the heating tubes are positioned; A³ are the tunnels through which the fire passes for heating the furnace, the principle of the tunnel being to prevent the flames from coming 60 into direct contact with any of the tubes; A⁴ is the flue connecting the furnace to the stack A⁵.

B are parallel substantially level heating tubes.

C are parallel distilling tubes which are slanted. The slanting tubes C at the lower end enter into the tanks D and D¹, D² and D³ are similar tanks connected by pipes D⁴ and D⁵, and out of the upper ends of tanks D² and D³ are overflow lines D⁶ and D⁷ connecting with suction line D⁸ leading into circulating pump E which is operated by motor E¹. Out of the same end of tanks D² and D³ are residuum lines D⁹ and D¹⁰ 70 which enter into the common residuum line D¹¹ which can be carried to any suitable destination, and on this residuum line is located pressure regulating valve D²⁷. Out of the bottom of tanks D, D¹, D², and D³ 75 are lines D¹² and D¹³ through which the residuum may be withdrawn along with any solid matter deposited in these tanks, or the solid matter alone forced out through these lines.

D¹⁴, D¹⁵, D¹⁶ and D¹⁷ are steam lines entering the tops of tanks D, D¹, D² and D³. Positioned on these tanks are manholes D¹⁸ and D¹⁹, and water gages D²⁰, D²¹, D²² and D²³, and out of the tops of these 90 tanks are vapor manifolds D²⁴ and D²⁵ entering vapor line D²⁶.

F is the discharge line from the circulating pump E to the heating tubes B, and on this discharge line is pressure gage F¹ 95 and pyrometer F², and also hopper G, having positioned in it steam line G⁴, connected with manifold G¹ which manifold connects by means of pipes G² and G³ to discharge line F. Also connected to the line F is supply line F³ which is to supply the raw material to the apparatus by means of any standard make of force pump which is not shown.

B¹ is discharge line from the heating tubes B to the top of the distilling tubes C and 105 having positioned in it pyrometer B².

H, and H¹ are reflux vapor lines, and positioned on them is pressure gage H², these

vapor lines enter into manifold H^3 and on this manifold is temperature gage H^4 , and from said manifold H^3 extends line H^6 through water cooling tank H^6 by means of 5 coils H^7 and discharges into the top of receiving tank J . On said receiving tank J is pressure relief valve J^1 , the gas relief line J^2 , pressure gage J^3 , liquid gage J^4 , and draw-off line J^5 .

10 $K^1, K^2, K^3, K^4, K^5, K^6, K^7, K^8, K^9, K^{10}, K^{11}, K^{12}, K^{13}, K^{14}, K^{15}, K^{16}, K^{17}, K^{18}, K^{19}, K^{20}, K^{21}, K^{22}, K^{23}, K^{24}, K^{25}, K^{26}, K^{27}, K^{28}, K^{29}$, and K^{30} are throttle valves.

15 A^6 is a pyrometer positioned in the furnace A^2 , and A^7 and A^8 are pyrometers positioned in the furnace A^1 .

Describing now the operation of the process. The material to be treated is forced into the apparatus through the line F^3 until the 20 heating tubes B and tanks D, D^1, D^2 and D^3 are filled and the lower end of the distilling tubes C are full of material to be treated at which time the circulating pump E is put and maintained in operation. Heat is maintained in the furnace A^2 and A^1 , and the oil 25 as it passes through the tubes B is raised to the desired temperature and this heated oil is passed from said heating tubes B into the top of distilling coil C and then allowed to 30 gravitate down through these tubes into either tank D or D^1 or both, and the oil flows from these tanks through connecting lines D^4 and D^5 into tanks D^2 and D^3 and part of the oil flows out of the upper end of 35 these tanks through line D^8 to supply pump E , and the residuum to be drawn off can be drawn off through line D^{11} or through any or all of the lines extending out of the bottom of the tanks D and D^1, D^2 , and D^3 , such 40 lines being marked D^{12} and D^{13} .

The supply of oil to the pump E is discharged back through discharge line F and positioned in said discharge line F is hopper G in which the non-re-active abrasive material 45 is placed, and same can be warmed by the steam line G^4 if desired, or any other means can be used for warming the same.

Valves K^{16} and K^{17} normally remain closed, while valve K^{19} remains open, with 50 the valves in this position, the manifold G^1 is filled to the desired quantity with a non-re-active abrasive material such as sand from the hopper G , and the valve K^{21} then closed, likewise the valve K^{19} , while valves 55 K^{16} and K^{17} are opened and thus forcing the oil to travel through the manifold G^1 and thus become charged with the non-reactive abrasive material contained in the manifold G^1 and force such abrasive material 60 through the heating tubes B and into and through the distilling tubes C into the tank D or D^1 and be withdrawn through line D^{12} while the oil overflows through line D^4 or D^5 into tank D^2 or D^3 where any further 65 settlement of the abrasive material can take

place and be drawn off from the bottom of said tanks through line D^{13} , and along with this abrasive material will be settled out of the oil more or less of its free carbon and other solid contents.

70

The oil after thus being settled is drawn out of these tanks through the suction line D^8 into the pump E and back through the heating tubes B and rest of the apparatus and a further supply of abrasive material is 75 added to the oil.

It will be understood that as many of these hoppers may be positioned on the discharge line or arranged so that a continuous supply of abrasive material can be mixed with the 80 oil undergoing treatment.

The object in having two sets of tanks as shown in the drawing is that in case the abrasive material used is of such a nature, or the other solids that settle out of the oil 85 are of such a nature, that they cannot readily be drawn from the bottom of any of these tanks, then one set of tanks can be in operation while the other set of tanks are cut out of the apparatus and cleaned; for instance, 90 tanks D and D^2 would be left in operation by the opening of valves $K^7, K^8, K^{24}, K^{26}, K^{12}$ and K^{14} , while tanks D^1 and D^3 will be cut off from the rest of the apparatus by the closing of valves $K^5, K^6, K^{29}, K^{28}, K^{11}, K^{15}$ 95 and K^{13} and the manheads of the sides of said tanks taken off and said tanks cleaned; they could be further cleaned by steam through lines D^{14}, D^{16} and D^{17} .

It will also be understood that a similar 100 series of tanks or traps for settling the abrasive material and carbon out of the oil can be positioned in any suitable place between the heating tubes B and the distilling tubes C and the settled oil discharged 105 into the top of the distilling tubes C .

The generated vapors will pass up through the vapor lines H and H^1 and any vapors liberated in the tanks D, D^1, D^2 , or D^3 will escape up through vapor line D^{24} 110 and D^{26} into the vapor line H , and as said vapors pass up through vapor lines H , more or less of the heavy vapors will be condensed out and return to the distilling tubes and heating tubes for further treatment, 115 while the remaining vapors pass through line H^6 through coil H^7 positioned in the water tank H^6 and are collected in a receiving tank J and withdrawn from same either continuously or intermittently 120 through line J^5 , while the uncondensed gases pass off either continuously or intermittently through line J^2 .

It will be seen by the above described method that it provides a process for continuously and automatically treating petroleum for the production of lower boiling point products and, while doing so, provides for an abrasive material to be mixed with the oil which will scour and keep pol- 125 130

ished the insides of the heating and distilling tubes and thus prevent deposits of carbon from forming thereon.

It will also be noted that provision is made for settling out of the oil, after it passes through either the heating tubes or both the heating and distilling tubes, as well as allowing the free carbon and other solid matters contained in the oil to settle out 10 automatically, and the settled oil subjected to further treatment.

It will be further understood that the principle of adding an abrasive material to the oil for the prevention of carbon formation on the tubes in which the oil is heated or distilled and the separating out of said oil all or part of such abrasive material applies to any process wherein it can be used, including such process wherein the oil is 20 heated under pressure and including such processes wherein the vapors generated are condensed under pressure.

It will be understood that the drawings herewith annexed are for the purpose of 25 showing the principle involved and are not for the purpose of confining the process to any particular design or construction of apparatus.

I claim as my invention:

30 1. A process of treating hydrocarbon oils consisting in passing the oil through a

closed receptacle seated in a heated zone subjecting the oil in said heated zone to a pressure and temperature sufficient to crack the oil and preventing the precipitated carbon 35 from rigidly adhering to the walls of the receptacle by scouring the walls with a substantially non-reactive abrasive material mixed in the oil in a finely comminuted form.

2. A process of treating hydrocarbon oils consisting in passing the oil through a closed receptacle seated in a heated zone subjecting the oil in said heated zone to a pressure and temperature sufficient to crack 45 the oil and preventing the precipitated carbon from rigidly adhering to the walls of the receptacle by scouring the walls with a substantially non-reactive abrasive material mixed in the oil in a finely comminuted form 50 such as sand.

3. A process of treating hydrocarbon oils consisting in passing the oil through a closed receptacle seated in a heated zone subjecting the oil in said heated zone to a 55 pressure and temperature sufficient to crack the oil and preventing the precipitated carbon from rigidly adhering to the walls of the receptacle by scouring the walls with an abrasive material mixed in the oil in a 60 comminuted form.

LELAND A. DUBBS.
